UNITED STATES PATENT OFFICE.

EDWIN PEAR MONROE, OF NEW YORK, N. Y.

SLIDE-VALVE.

SPECIFICATION forming part of Letters Patent No. 293,975, dated February 19, 1884.

Application filed January 17, 1883. (No model.)

To all whom it may concern:

Be it known that I, EDWIN PEAR MONROE, of the city, county, and State of New York, have invented a new and useful Improvement 5 in Slide-Valves, of which the following is a specification.

The invention relates to the slide-valve of a steam-engine cylinder; and it consists in constructing the valve with a cast-iron body and 10 with a face-plate of gun metal or analogous alloy, the said face-plate being provided with pockets filled with Babbitt or other anti-friction metal.

In the accompanying drawings, Figure 1 is 15 a longitudinal section of the valve on the line xx of Fig. 2. Fig. 2 is a plan view of the under side of the face-plate. Fig. 3 is a transverse section on the line yy of Fig. 2, showing the manner of uniting the valve-body and face-plate.

Similar letters of reference indicate like parts.

A is the body of the valve, made of cast-iron in the usual form.

25 B is the face-plate, of gun metal or analogous composition.

In the under or working side of the face-plate are formed pockets C. Said pockets are preferably placed angularly across the face-plate, as shown in Fig. 2, and are made of dovetail shape in cross-section, as represented in Fig. 1—that is to say, the bottoms D of said pockets are larger in area than the orifices E.

In the upper side of the face-plate B, I form 35 a mortise, also of dovetail shape in cross-section. This mortise receives a correspondingly-shaped tenon, F, formed on the valve-body A.

In practice, I cast the face-plate B separately 40 with the mortise and pockets, as described. Then, while the casting is still hot, I insert the tenon F into the mortise in the face-plate. As the face-plate cools it contracts firmly upon the tenon, so that the face-plate thus becomes 45 firmly united to the body of the valve. When the valve thus constructed is subjected to the heat of the steam in the valve-chest, the iron body A expands more than the composition face-plate B, the ratio of expansion of cast-iron being greater than that of the alloy, and

hence the tenon fits all the more tightly in its mortise. I tin the interior of the pockets C by any known way, and then fill said pockets with Babbitt or anti-friction metal in a molten state. When the Babbitt has cooled and 55 hardened, I bring the valve-face to a smooth and uniform surface. The object of tinning the interior of the pockets is to cause the anti-friction metal firmly to adhere to the sides. The dovetail form of the pockets prevents the 60 resulting plugs of Babbitt from falling out under any circumstances. I prefer a number of small pockets in the valve-face to a few large pockets, because the aforesaid arrangement leaves numerous partitions H, which serve to 65 strengthen the face-plate. The object of placing the pockets diagonally instead of straight across the valve-face is to cause the two edges, which in the last-mentioned case would stand at right angles to the line of longitudinal motion of the valve, to be presented at an acute angle thereto. This decreases the likelihood 70 of abrasion of said edges.

I have found by experiment that the above-described construction of a slide-valve offers 75 great advantages in the prevention of friction of the valve on its seat and in the consequent diminution of wear of the valve. This is an important desideratum, especially in locomotive-engines, where worn and leaky slide-valves, 80 are constant sources of expense and of waste of steam.

I claim as my invention—

1. In a slide-valve, the combination of a cast-iron body, a face-plate of gun metal or 85 analogous alloy, and plugs or blocks of anti-friction metal inserted and held in mortises or pockets in the face-plate, substantially as described.

2. A slide-valve having an iron body provided with a dovetail tenon, and a gun-metal or composition face-plate provided with a corresponding mortise, the body and face-plate being united by said tenon and mortise, substantially as described. 90

3. In a slide-valve, a face-plate of gun metal or analogous alloy, containing pockets of dovetail cross-section, filled with Babbitt or other anti-friction metal, substantially as described. 95

4. In a slide-valve, and in the face-plate 100

thereof, pockets containing Babbitt or other anti-friction metal, each pocket having two of its parallel outer edges placed at an acute angle to the longitudinal axis of the valve-face, substantially as described.

5. The method herein set forth of attaching Babbitt-metal plugs to and in the gun-metal face-plate of a slide-valve, consisting in forming said face-plate with pockets of dovetail

cross-section larger at the base than at the orifice, tinning the interior of said pockets and filling the same with melted Babbitt metal, substantially as described.

EDWIN P. MONROE.
